ALFRED JOHN KEAST AND HAROLD KEAST, OF SAN JOSE, CALIFORNIA, ASSIGNEES TO CALIFORNIA FRUIT CANNERS ASSOCIATION, OF SAN FRANCISCO, CALIFORNIA, A CORPORATION OF CALIFORNIA.

EXHAUST-BOX FOR CANS.

1,074,869.

Specification of Letters Patent.

Patented Oct. 7, 1913.

Application filed August 7, 1912. Serial No. 713,903.

To all whom it may concern:

Be it known that we, ALFRED JOHN KEAST and HAROLD KEAST, citizens of the United States, residing at San Jose, in the county 5 of Santa Clara and State of California, have invented certain new and useful Improvements in Exhaust-Boxes for Cans, of which the following is a specification.

Our invention relates to that class of heating chambers used in the canning art for giving what is termed the "first cook"; that is, expelling the air from the filled, but still open cans, prior to capping or sealing them, after which they are subjected to the "second" or final cooking. These devices are 15 from their function usually termed "exhaust-boxes".

The object of our invention is to provide a compact apparatus in which the cans may, 20 nevertheless, be carried through a relatively long course to give sufficient time for the purpose sought.

To this end our invention consists in the novel exhaust-box which we shall now fully 25 describe by reference to the accompanying drawings, in which—

Figure 1 is a plan of our exhaust-box, the cover being removed. Fig. 2 is a vertical sectional view of the same with the cover 30 in place. Fig. 3 is a vertical section on the line $\alpha-\alpha$ of Fig. 1, looking outwardly in the direction of the traveling conveyer 12.

1 is a supporting column which carries the radial arms 2, in the extremities of which is 35 mounted the circumferential band 3, supporting the cover 4. In socket blocks 5 of the arms 2 are seated balls 6, upon which are supported the rings 7. These rings may be in number to suit; we have here shown five. 40 They are independent of each other and form a horizontally disposed series which constitutes the floor of the box. The rings have rotation imparted to them, adjacent ones rotating in relatively opposite directions. 45 To effect this there is carried in bearings 22 on arms 23 supported by the column 1, a shaft 8 with a pulley 9. Upon the shaft 8 are pinions 10, two on one side and three on the other side of the center of the ring series. 50 Under each ring 7 is an annular gear 11 meshing with the respective shaft pinions. This arrangement provides for the rotation above mentioned. Upon the exterior of the ring series and tangential thereto is a travel-

ing conveyer 12. Above the ring series and 55 radially directed is a feed can-pathway 13. This pathway at its outer end communicates with the conveyer 12, and at the point of communication is a rail 14 which is disposed to deflect the cans 15, in precession, from the 60 conveyer into the pathway 13. At its inner end the pathway 13 communicates with the innermost ring 7 of the ring series.

16 are two separated radially directed endless traveling belts set on edge. The 65 adjacent courses of these belts bound the pathway 13 and move from circumference to center. These courses are pressed inward by springs 25 against the cans and they direct said cans through the pathway 13 and 70 deliver them to the innermost ring 7. The outer courses of the belts 16 move from center to circumference.

Suspended by hangers 17 from overlying 75 arms 24 are can-guard-rails 18 which separate the rings 7. These rails are made to serve the additional function of heaters and for this purpose they are made of pipes which are perforated, in order to admit steam furnished them by suitable steam connections 19, to the inclosure formed by the cover and the ring-series. The rails 18 are not continuous. Each terminates at one end or the other sufficiently short of the outward moving courses of the radial belts 16, to 80 leave spaces 20, of communication from one ring to the next ring, the arrangement being such that the space from the inner ring to the second ring is on one side of the radial feed pathway; the space from said second 90 ring to the third is on the other side of said pathway; the space from the third to the fourth is on the first side, and so on, this arrangement being thus consistent with the relatively reverse rotation of the rings, so 95 that the cans may be continuously advanced. It will be seen that one border of each inter-ring communicating space 20 is an adjacent portion of the outmoving course of one or the other of the belts 16 so that the cans are 100 brought into contact with these portions and by them are deflected through the spaces from one ring to the other. Deflecting rails 21 serve to direct the cans from the outermost ring to the tangential conveyer 12 by 105 which they are carried off.

The operation of the device is as follows:—The cans 15 in procession are car-

ried forward by the conveyer 12 until, meeting the rail 14, they are deflected into the pathway 13. In this they are directed by the inward moving courses of the belts 16 to and are delivered upon the innermost ring 7 of the ring series. Upon this ring they are carried around in one direction until they reach the first communication space 20. Here meeting the outward moving course of the belt 16 on that side they are deflected upon the second ring, which, rotating in the reverse direction, carries them around to the second space 20, where meeting the outward moving course of the other belt 16, they are deflected through said space to and upon the third ring by which they are carried back again in the first direction, and so on until, arriving at the rails 21, they are finally deflected to and upon the conveyer 12 by which they are carried off.

Steam admitted to the hollow perforated guide rails 18 serves to heat the inclosure.

Having thus described the invention what is claimed as new and desired to be secured by Letters Patent is—

1. In an exhaust-box, the combination of a series of horizontally disposed concentric independent rings; means for rotating adjacent rings in relatively opposite directions; means for feeding the cans to one of the terminal rings of the series; means for discharging the cans from the other terminal ring of the series; means for automatically transferring the cans upon the completion of their travel with one ring to the next ring throughout the series; means for covering said rings to form an inclosure for the cans; and means for supplying heat to said inclosure.

2. In an exhaust-box, the combination of a series of horizontally disposed concentric independent rings; means for rotating adjacent rings in relatively opposite directions; means for feeding the cans to the innermost ring of the series; means for discharging the cans from the outermost ring of the series; means controlled by the feeding means for automatically transferring the cans upon the completion of their travel with one ring to the next ring throughout the series; means for covering said rings to form an inclosure for the cans; and means for supplying heat to said inclosure.

3. In an exhaust-box, the combination of a series of horizontally disposed concentric independent rings successively communicating alternately on either side of a radially directed infeeding can pathway; means for rotating adjacent rings in relatively opposite directions; means for discharging the cans from the outermost ring; a radially directed infeeding can pathway to the innermost ring; means for feeding the cans through said radially directed infeeding

pathway to the innermost ring, said feeding means being adapted at the communications of the rings with each other to automatically transfer the cans from one ring to the next ring throughout the series; means for covering said rings to form an inclosure for the cans; and means for supplying heat to said inclosure.

4. In an exhaust-box, the combination of a series of horizontally disposed concentric independent rings; means for rotating adjacent rings in relatively opposite directions; means for directing the cans to the innermost ring of the series comprising a pair of separated endless traveling belts radially directed relative to the ring series, the adjacent courses of said belts moving from circumference to center of said ring series and adapted to advance the cans between them, and the outer courses of said belts moving from center to circumference of said ring series; fixed guard rails for the cans separating one ring from the next ring, said rails terminating short of the outward moving courses of said belts alternately on opposite sides thereof to leave alternate spaces of communication for the cans from one ring to the next ring, said spaces having for one boundary the outward moving course of one belt or the other belt alternately whereby the cans by contact with said courses are transferred through said spaces from one ring to the other successively; means for covering said rings to form an inclosure for the cans; and means for supplying heat to said inclosure.

5. In an exhaust-box, the combination of a series of horizontally disposed concentric independent rings; means for rotating adjacent rings in relatively opposite directions; means for directing the cans to the innermost ring of the series comprising a pair of separated endless traveling belts radially directed relative to the ring series, the adjacent courses of said belts moving from circumference to center of said ring series and adapted to advance the cans between them, and the outer courses of said belts moving from center to circumference of said ring series; fixed guard rails for the cans separating one ring from the next ring, said rails consisting of perforated pipes terminating short of the outward moving courses of said belts alternately on opposite sides thereof to leave alternate spaces of communication for the cans from one ring to the next ring, said spaces having for one boundary the outward moving course of one belt or the other belt alternately whereby the cans by contact with said courses are transferred through said spaces from one ring to the other successively; means for covering said rings to form an inclosure for the cans; and means for supplying heat to said perforated guard-rail pipes.

6. In an exhaust-box, the combination of a series of horizontally disposed concentric independent rings; means for rotating adjacent rings in relatively opposite directions; 5 a conveyer for the cans exterior to the ring series and tangentially directed relative thereto; a feed pathway for the cans radially directed from circumference to center of the ring series, said pathway communicating at its outer end with the tangential can conveyer; means at said communication to deflect the cans from the conveyer into said 10 pathway; means bordering said pathway for directing the cans therethrough to the innermost ring of the series comprising a pair of separated endless traveling belts with their adjacent courses moving inward and receiving the cans between them, and their outer courses moving outward; fixed guard-rails 15 for the cans consisting of perforated pipes separating one ring from the next ring, said rails leaving spaces of inter-ring communication for the cans on alternate sides of the outward moving courses of the belts, said spaces having for 20 one boundary said outward moving courses whereby the cans by contact therewith are transferred from one ring to the other successively; means for deflecting the cans from the outermost ring to the tangential conveyer at a point beyond the can-feed pathway; means for covering the rings to form an inclosure for the cans; and means for 25 supplying heat to said inclosure.
7. In an exhaust-box, the combination of 30 a series of horizontally disposed concentric independent rings; means for rotating adjacent rings in relatively opposite directions; a conveyer for the cans exterior to the ring
- series and tangentially directed relative thereto; a feed pathway for the cans radially directed from circumference to center of the ring series, said pathway communicating at its outer end with the tangential can conveyer; means at said communication to deflect the cans from the conveyer into said 35 pathway; means bordering said pathway for directing the cans therethrough to the innermost ring of the series comprising a pair of separated endless traveling belts with their adjacent courses moving inward and receiving the cans between them, and their outer courses moving outward; fixed guard-rails for the cans consisting of perforated pipes separating one ring from the next ring, said rails leaving spaces of inter-ring communication for the cans on alternate sides of the outward moving courses of the belts, said spaces having for one boundary said outward moving courses whereby the cans by contact therewith are transferred from one 40 ring to the other successively; means for deflecting the cans from the outermost ring to the tangential conveyer at a point beyond the can-feed pathway; means for covering the rings to form an inclosure for the cans; and means for supplying heat to said 45 perforated guard-rail pipes.
